UNITED STATES PATENT OFFICE.

FRANK G. MARBACH, OF CLEVELAND, OHIO, ASSIGNOR TO CHAMPION REGISTER COMPANY, OF CLEVELAND, OHIO, A CORPORATION OF OHIO.

SEPARABLE CASE AND REGISTER.

1,187,356.

Specification of Letters Patent. Patented June 13, 1916.

Application filed August 14, 1914. Serial No. 856,798.

To all whom it may concern:

Be it known that I, FRANK G. MARBACH, a citizen of the United States, residing at Cleveland, in the county of Cuyahoga and State of Ohio, have invented a new and useful Improvement in Separable Cases and Registers, of which the following is a specification.

This invention relates generally to account registers.

Heretofore several types of account registers have been made and used, one construction involving a wooden frame or rack upon which rests the register proper comprising a plurality of hinged bill leaves. In the bottom of the wooden frame has been arranged a cash drawer and recorder and the register has sometimes been made removable from the frame so that it can be placed in the safe or vault as a protection against fire. This method of manufacture has certain drawbacks or objections and among them may be mentioned the difficulty which sometimes occurs in fitting the cash drawer and recorder in the sections provided for them.

The object of my invention therefore is to avoid all of the objections incidental to building the register and its appurtenances into the protective case, and my invention therefore consists in providing a protective metallic case having an upwardly opening top or cover and a downwardly and outwardly opening front and arranging in this case a skeleton frame which frame is made entirely independent of the case and is adapted to carry not only the bill leaves in proper order and position but also the cash drawer and recorder.

The invention consists in making this frame carrying these parts independent of, and separable from the case, the connection means being such that the frame and its parts can be quickly and easily attached to and detached from the case whenever desired.

The invention consists also in certain details of construction and novelties of combination, all of which will be fully described hereinafter and pointed out in the claims.

In the drawings forming a part of this specification: Figure 1 is a perspective view of an account register embodying my present invention. Fig. 2 is a view showing the frame and connected parts separated and detached from the case. Fig. 3 is a detail per-

spective view of the skeleton frame, and, Figs. 4, 5 and 6 illustrate details of construction.

Referring to the drawings, A indicates the sheet metal case proper which is constructed in the manner fully described and claimed in my application Serial Number 860,040, this sheet metal case being filled with asbestos or other fire resisting material. The cover B opens upwardly and the front C opens outwardly and downwardly. The bottom D is perfectly smooth. Within this case I place a skeleton frame E which is constructed of upper and lower pieces of angle iron F properly spaced apart by angle uprights G, all of these pieces being united by spot-welding or other suitable process. The uprights at the front instead of being of angle iron are made flat and the front member of the bottom portion is angled as shown at F' in order to embrace the forward edge of the bottom as most clearly shown in Fig. 5. Suitable brace rods can be employed for giving the proper rigidity to this skeleton frame. Upon the top of the skeleton frame I preferably place a covering plate H, the rear end of which is inclined upwardly as shown at I, this inclined portion being braced by suitable braces I', and pivoted to the forward side of said inclined portion are the bill leaves K which are constructed in accordance with the bill leaf shown and described in my application filed of even date herewith. At each side of the skeleton frame are the drawer guides L, which are made of channel iron spot-welded to the uprights of the skeleton frame, the channel faces being turned inwardly to receive slides M upon the cash drawer N and register drawer O, these slides M being of channel iron also spot-welded to the outer sides of the said drawers N and O, the dimensions of the slides being such as to fit snugly within the guides M and slide freely back and forth.

The opposite sides of the drawers N and O are provided with slides M' which project laterally in opposite directions from the bottom portions of said drawers and are adapted to engage the guides L', these guides L' being formed from a piece of channeled and flanged metal arranged upon a brace strip and spot-welded to the skeleton frame as most clearly shown in Figs. 3 and 5. From this it will be seen that each drawer has a

slide at the bottom and also adjacent the top, which slides work in metal guides attached to and constituting a part of the skeleton frame.

- 5 The rear end of the skeleton frame is provided with two or more rearwardly projecting headed screws or hooks P which are adapted to engage key-hole shaped openings or eyes Q, arranged in the rear wall of the 10 case and by means of this construction the skeleton frame and its attached parts can be quickly and easily attached to, and detached from the case, and when the skeleton frame is properly positioned in the case the 15 angle iron front F' at the bottom will overlap the forward edge of bottom of case and will be engaged by the shouldered portion of the front or door when said front is turned up for the purpose of closing the 20 case. By means of this skeleton frame, which is shaped in suitable dies, absolute accuracy of parts can be obtained and consequently the drawers will fit properly in their respective places, whereas, if guiding spaces 25 are built into the sheet metal case there is likely to be some slight inaccuracy owing to expansion and contraction during the brazing and welding process and it is well known that any slight inaccuracy at these 30 points renders it extremely difficult at times to fit the drawers properly therein; and the labor incidental to properly fitting these parts adds considerably to the cost of the 35 register as a whole.
- By means of my present invention the various parts of the case can be punched up and put together and the case as a whole finished off. The skeleton frame is shaped up, assembled and all of its parts connected

thereto, and then this skeleton frame with its attached parts can be quickly and easily arranged in the protective case and consequently a great deal of time and labor is thereby saved, as it will be readily understood that any desired number of cases can be made and a similar number of skeleton frames and attached parts can also be constructed and the frame and its attached parts will always be readily receivable in and attachable to the case. 50

What I claim is:—

1. In an account register a frame having a downwardly extending flange at its forward end and a rearwardly projecting fastening means at its rear end, a rearwardly and upwardly projecting plate attached to the rear end of frame, said frame being provided with drawer slides and adapted to receive drawers as set forth. 55
2. In a device of the kind described, a skeleton frame, having drawer guides arranged within the same, drawers sliding therein and an inclined plate attached to the top of frame and bill leaves pivoted to said plates as described. 60
3. In a device of the kind described, an angle iron skeleton frame adapted to be arranged in a case, said frame having drawer guides within the frame, drawers sliding therein, a plate attached to the top of frame 70 and having an inclined rear portion, and bill leaves pivoted to said inclined portion or plate as described. 65
